US00D732567S

(12) **United States Design Patent**
Moon et al.

(10) **Patent No.:** US D732,567 S
(45) **Date of Patent:** ** Jun. 23, 2015

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Ji-Young Moon**, Seoul (KR); **Min-Ju
Kim**, Seoul (KR); **Ho-Young Lee**, Seoul
(KR)

(73) Assignee: **Samsung Electronics Co., Ltd.,**
Suwon-si (KR)

(**) Term: **14 Years**

(21) Appl. No.: **29/457,159**

(22) Filed: **Jun. 7, 2013**

(30) **Foreign Application Priority Data**

Feb. 23, 2013 (KR) 30-2013-0009545

CLAIM

The ornamental design for a display screen or portion thereof with graphical user interface, as shown and described.

DESCRIPTION

FIG. 1 is a front view of a display screen or portion thereof with graphical user interface, showing our new design; FIG. 2 is a front view of a second embodiment thereof; and, FIG. 3 is a front view of a third embodiment thereof. The broken lines represent environment and form no part of the claimed design.
